UNITED STATES PATENT OFFICE.

HAROLD B. PULLAR, OF LAWRENCEVILLE, ILLINOIS.

BITUMEN PRODUCT.

1,248,909.

Specification of Letters Patent.

Patented Dec. 4, 1917.

Application filed June 8, 1916. Serial No. 102,427.

To all whom it may concern:

Be it known that I, HAROLD B. PULLAR, a citizen of the United States of America, and resident of Lawrenceville, Lawrence 5 county, Illinois, have invented a certain new and useful Improvement in Bitumen Products, of which the following is a specification.

My invention relates to improvements in 10 bitumen products, and the purpose of my invention is to provide a product of this character which, because of its construction, formation and characteristics, is capable of a wide variety of uses such as expansion joints 15 for pavements, insulation, water-proofing and roofing.

In the drawing I illustrate one embodiment 20 of my invention adapted for use as packing material in connection with expansion joints for pavements and in fact wherever expansion joints are provided for, but it will be obvious to those skilled in the art, after having obtained an understanding 25 of my invention from the disclosures herein made, that the principles of my invention are capable of application to various other uses, without departing from the scope and spirit of my invention and I wish it so understood.

30 Referring to the accompanying drawing, I have illustrated a strip or slab of my improved material in the process of construction, Figure 1 being a diagrammatic view illustrating the process of forming a slab 35 or strip of bituminous compound or asphalt of such character as adapted for expansion joints for pavements.

Fig. 2 is a similar view but illustrating 40 my improved method of combining or incorporating the fabric with the body of the slab or strip.

Fig. 3 is a perspective view of a completed expansion joint strip.

It has been the practice in the past to 45 construct expansion joints in two general ways, viz., by pouring or forming the joint at the place where the joint is to be installed, and by previously preparing the joint at a plant or factory so that it may be 50 installed at any time and place. The former

method merely consisted in heating the bitumen or asphalt or whatever compound or material is used, to a molten state and pouring a quantity of such melted material in the space provided for the joint. The expansion joint produced in this manner, while it has certain advantages, is expensive, inconvenient and slow to handle and it lacks uniformity and tensile strength. In accordance with the latter method it is the practice to form the joints of long flat strips or slabs of bituminous or asphalt material and incorporate therein either on the outer faces or throughout the interior, cloth, fabrics or other materials such as roofing paper, felt, 60 and the like, for the purpose of giving the slabs tensile strength. It has even been attempted to use a mixture of ingredients such as pulverized roofing paper, sand, silica and a bituminous binder in various proportions. 70 These various types have been more or less unsuccessful because of various inherent conditions. For instance where the fabric or cloth is used on the outer face or faces of the slabs or strips the fabric entirely destroys the bonding effect or adherence of the strip with respect to the pavement sections, and the joint works out of position. On the other hand where the fabric is incorporated 75 through the center of the joint strip, it has the effect of dividing the strip into two sections which in time separate and work out of place. So also where alternate layers of bitumen and felt, cloth or paper are used it not only divides the strip into numerous 80 sections but decreases the resilient quantities of the joint and destroys its ability to follow the movement of the pavement sections. I have conceived the idea of embedding or incorporating a fabric into the slab or strip in 85 proximity to one or both faces of strip, but in doing this I employ a fabric which has an open mesh so that compound or material extends actually through the fabric and in actual contact with the sections of pavement. 90 This construction creates a bonding or adhering effect equal to that of a poured joint, and at the same time imparts to the joint the maximum tensile strength without affecting 95 its resiliency and other desirable character- 100

istics. Furthermore the material is confined by the fabric against spreading or working out of place. In making a joint in accordance with my invention I take a quantity of 5 pure asphalt or bituminous compound or suitable substance for the purpose, such as indicated at A in the drawing and roll or otherwise form it into a flat slab B of the required thickness. I have indicated a pair 10 of rolls C for this purpose but it is understood that any usual or approved form of apparatus may be employed. I then incorporate a layer of cloth or fabric D preferably in both sides of the slab, although 15 where the product is to be used for roofing boards for instance, this fabric may be incorporated in one side only of the slab. This fabric D is of such structure that its mesh is open. I have found that a fabric 20 woven or formed with a mesh within the range of about ten to about two hundred openings will be effective to permit the bituminous material to readily pass through the openings and in effect permit the fabric to 25 become intimately and completely embedded within the body of the slab material. This fabric may be of any suitable material for the purpose and the particular weave is non-essential. Satisfactory results may be ob- 30 tained by laying individual cords or wires in different directions so as to form a layer or stratum thereof, the essential requirement being that these cords be laid so as to provide spaces therebetween. I find in practice 35 that a fabric having a mesh of about 140 to 150 openings per square inch is best adapted for this purpose because the mesh openings are of sufficient size for the purpose and at the same time the fabric imparts to the 40 structure a sufficient tensile strength. In practice I apply the fabric to the body of bituminous material which is resilient or of a sort of rubbery consistency by mechanically pressing or otherwise forcing it into 45 the surfaces of the slab to the proper degree and then subjecting the surface portions of the slab to a heating process which melts the bituminous material and causes it to pass through the fabric and intimately intermingle therewith, this being practically impossible where a close woven fabric is used. This I find to be best accomplished by passing the slab with the fabric therewith between a set or sets of rolls E which are 50 heated to a degree sufficient to melt the bituminous material. This flows the bituminous material through and around the openings of the fabric and thoroughly and intimately associates the fabric material and 55 forms an integrally connected thin bonding film on the outer surface of the fabric. Not only this but the melted bituminous compound or asphalt where cloth or paper fabric or cords are used thoroughly impreg-

nates the fabric and very effectively preserves it against deterioration indefinitely 65 after the joint has been installed in place. Of course, it is understood that the heating of the surface portions of the body of the material is not sufficient to distort or otherwise affect the main portion or body thereof. The resulting product, which is illustrated 70 as complete in Fig. 3 of the drawing, constitutes in a sense an integral unit which can be made in large quantities in the plant or factory and conveniently handled and shipped 75 to the place where it is to be used. When installed in position between the sections of pavement, the fact that it has a portion or film of the bituminous body on its outer 80 surfaces causes it to bind or adhere to the pavement sections as readily and efficiently as in a poured joint. Of course in the actual manufacture the slabs are preferably made considerably larger in area than that required 85 for a single expansion joint, but when the product is to be used as an expansion joint this large slab may be cut in any desired manner into strips of the proper width. Where the product is to be used as 90 roofing board for instance, the slab of course would be cut to the required size for this purpose. Furthermore where the product is used for roofing purposes it might be found advisable to eliminate the fabric from one 95 side thereof, but of course this is a matter of choice and dependent upon the various conditions and requirements.

I claim:

1. Packing material for the purposes described comprising a body of resilient asphaltic material in flat slab like form having in intimate association therewith adjacent and substantially parallel with its surfaces an open woven fabric, said asphaltic 100 material extending through the fabric, so that the material on one side of the fabric is integral with the material on the other side of the fabric through the openings in the fabric.

2. The improvement herein described comprising a narrow, elongated strip of resilient asphaltic material in flat slab-like form, of uniform thickness and of comparatively low tensile strength, in combination with strips 105 of fabric of comparatively high tensile strength disposed parallel within the body of material and spaced apart, to provide a comparatively thick body of material therebetween, and a thin film of material on each 110 face of the strip, said fabric strips being in extremely close relation to the surfaces of said body of material, and having an open mesh through the openings of which the body of material extends and is integrally 115 connected with the films of material on the faces of the strip.

3. The process herein described consisting

in rolling or otherwise forming a mass of bitumen into a flat elongated strip of uniform thickness, applying an open woven fabric strip to each face of said strip and 5 then subjecting the surface portions of the slab to sufficient heat and pressure to melt the bitumen and cause it to flow through the mesh of and into intimate relation to the

fabric and form a thin film of material on the exposed outer surface of said fabric. 10

Signed at Lawrenceville, Illinois, this 24th day of May, 1916.

HAROLD B. PULLAR.
